SLITTING AND WINDING MACHINE

William M. Stocker, Hollis, N. Y., assignor to
 Cameron Machine Company, Brooklyn, N. Y., a
 corporation of New York

Application June 25, 1940, Serial No. 342,316

3 Claims. (Cl. 164—65)

The present invention relates to slitting and winding machines of the type that employs two surface winding drums, and has for its main object and feature the provision of means to quickly adjust the machine to rotate the drums in either direction while maintaining the rotation of the slitter shaft in the same direction.

In the accompanying drawings the invention is disclosed in a concrete and preferred form in which:

Fig. 1 is a view in side elevation of so much of a slitting and winding machine as is necessary to an understanding of the invention;

Fig. 2 is a diagrammatic view of a machine embodying shear-cut slitter elements;

Fig. 3 is a diagrammatic view of a machine embodying score-cut slitter elements;

Fig. 4 is a view of the parts shown in Fig. 1 looking in the direction of arrow X of Fig. 1 with the parts so adjusted as to drive the slitter shaft from the intermediate gears;

Fig. 5 is a view similar to Fig. 4, but showing the parts so adjusted as to drive the slitter shaft from one of the winding drums; and

Fig. 6 is a detail sectional view substantially on the plane of line 6—6 of Fig. 1.

1 and 2 indicate two surface winding drums by means of which slitted material 3 is wound upon a winding shaft (not shown) in a well-understood manner. Said drums are provided with gears 4 and 5 that mesh with an intermediate gear 6. Motion is imparted to the machine by a suitable means such as a motor or a pulley connected to one of the drums or to the intermediate gear. In the present instance, a pulley 7 is shown mounted on shaft 8 of intermediate gear 6. It will be understood that rotation of pulley 7 can be effected in either direction and that as a consequence rotation of the winding drums can be effected in either direction.

9 indicates a slitter shaft carrying a suitable slitter means such as backing roller 10 with which cooperate score-cut slitters 11 (Fig. 3) or such shaft may carry shear-cut slitters 12 that cooperate with complementary shear-cut slitters 13 (Fig. 2).

W indicates a web of paper or other flexible material that is to be slit and wound. In the exemplification of the invention shown in Fig. 3, the slitted sections pass directly from backing roller 10 over the front of winding drum 2, the direction of rotation of the various parts being in the direction of the arrows shown in solid lines. If, however, it is desired to wind the sections with the other side out, then the direction

of rotation of the drums is reversed, as shown by the arrows in dotted lines, and the slitted sections are led in between the drums and over the back of winding drum 2. It will be noted that slitting means 10 and 11 rotate in the same direction in both instances. In the exemplification of the invention shown in Fig. 2, exactly the same thing occurs, except that an idler roller 14 is interposed intermediate slitting means 12 and 13 and winding drum 2 because the web must pass straight between the slitting means and cannot be trained around shear-cut slitter 12.

The means for driving slitter shaft 9 always in the same direction regardless of the direction of rotation of the drums are as follows: 15 indicates an additional gear on winding drum 2, and 16 and 17 denote two gears, slidable on slitter shaft 9. Gear 16 is adapted in one position (Fig. 4) to mesh with intermediate gear 6, at which time gear 17 is out of mesh with additional gear 15 on drum 2. When rotation of the winding drums is reversed (Fig. 5), gear 16 is brought out of mesh with intermediate gear 6, and gear 17 is brought into mesh with additional gear 15 on drum 2.

Preferably, gears 16 and 17 are moved simultaneously, and this can be accomplished by any suitable means. In the present instance, gears 16 and 17 are carried by a sleeve 18 slidable on slitter shaft 9 and rotating with shaft by means of key or feather 19. A bifurcated member 20 engages a groove 21 in said sleeve and is carried by slidable shaft 22 having rack 23. A pinion 24, rotatable by handwheel 25, engages said rack whereby gears 16 and 17 can be shifted in the manner previously described. To render it unnecessary to gage the sliding movement of shaft 22, suitable automatic latching means are employed which, in the present instance, take the form of a spring-pressed ball 26 carried by bearing 27 in which shaft 22 slides, and said shaft 22 is provided with recesses as 28 into which ball 26 snaps when shaft 22 has been moved the correct distance.

I claim:

1. In a slitting and winding machine having a rotatable slitter shaft, and having two surface winding drums provided with gears that mesh with an intermediate gear, said gears and said intermediate gear being reversibly rotatable, and means to rotate the slitter shaft always in the same direction regardless of the direction of rotation of the drums including: an additional gear on one of the drums, and two gears rotatable with the slitter shaft but slidable thereon,

one of said two gears being placed in mesh with the intermediate gear when the drums are to be rotated in one direction and out of mesh with said intermediate gear when the drums are to be rotated in the other direction, and the other of said two gears being placed in mesh with the additional gear on one of the drums when said drums are to be rotated in said other direction and out of mesh with said additional gear when the drums are to be rotated in the first-mentioned direction.

2. In a slitting and winding machine having a rotatable slitter shaft, and having two surface winding drums provided with gears that mesh with an intermediate gear, said gears and said intermediate gear being reversibly rotatable, means to rotate the slitter shaft always in the same direction regardless of the direction of rotation of the drums including: an additional gear on one of the drums, and two gears rotatable with the slitter shaft but slidable thereon, one of said two gears being placed in mesh with the

intermediate gear when the drums are to be rotated in one direction and out of mesh with said intermediate gear when the drums are to be rotated in the other direction, and the other of said two gears being placed in mesh with the additional gear on one of the drums when said drums are to be rotated in said other direction and out of mesh with said additional gear when the drums are to be rotated in the first-mentioned direction, and means to simultaneously 10 shift the two gears on the slitter shaft.

3. In a slitting and winding machine having a rotatable slitter shaft, and having two surface winding drums provided with gears that mesh with an intermediate gear, said gears and said 15 intermediate gear being reversibly rotatable, and means to rotate the slitter shaft always in the same direction notwithstanding the direction of rotation of the drums including: transmission means to drive said slitter shaft from one of the 20 drum gears or from the intermediate gear.

WILLIAM M. STOCKER.
